UNITED STATES PATENT OFFICE.

ARCHIBALD E. McNITT, OF CHICAGO, ILLINOIS.

MIXER.

No. 905,092.

Specification of Letters Patent.

Patented Nov. 24, 1908.

Application filed January 21, 1908. Serial No. 411,958.

To all whom it may concern:

Be it known that I, ARCHIBALD E. McNITT, a citizen of the United States, residing at Chicago, in the county of Cook and State 5 of Illinois, have invented certain new and useful Improvements in Mixers, of which the following is a specification.

This invention relates to that class of apparatus especially adapted to be used for 10 mixing building material, as with sand, cement, and crushed stone.

It has been customary to mount the revoluble mixer body upon rollers, but considerable objection is found with such a construction, as sand, gravel and other matter 15 readily contacts said rollers, thus resulting in greatly increasing the friction thereof, as well as quickly wearing out the sides of the mixer body. In my improved construction, 20 the revoluble mixer body is suspended in a suitable manner so as to obviate these difficulties.

One of the objects of my invention is to construct a mixer in such manner that the 25 revoluble mixer body may be suspended from suitable frame work so as to readily and efficiently perform the mixing operation.

Another object is to arrange the baffle or 30 mixing plates in the interior of the mixing chamber so as to not only thoroughly mix the material therein but to also provide an even and uniform feed.

Another object is to construct a telescopic 35 chute or funnel which is capable of being readily manipulated back and forth so as to positively regulate the amount of material to be discharged from the mixer.

Another object is to construct the front 40 head of the mixer body so as to enable the telescopic chute to effectually coöperate therewith for permitting constant control as to the amount of material to be discharged.

The invention consists in the features of 45 construction and combination of parts hereinafter described and claimed.

In the drawings, Figure 1 is a top or plan view of my improved mixer; Fig. 2 a vertical section thereof; Fig. 3 a cross section taken on line 3—3 of Fig. 2 looking in the direction of the arrow; Fig. 4 a similar view to Fig. 3 as used with a cable; and Fig. 5 a side elevation with the supporting frame in section showing the drum suspend- 55 ed by means of cables.

My improved mixer 6 is suitably mounted

within a frame which, as shown, comprises top and bottom longitudinal beams 7 and 8, respectively, retained by vertical and cross supports 9, as usual. A revoluble shaft 10 60 is disposed lengthwise upon and centrally of said frame, and is mounted in journal boxes 11. Upon the rear end of this revoluble shaft 10 is keyed a sprocket wheel 12, and immediately below this sprocket wheel is a 65 stub shaft 13, likewise having a sprocket wheel 14 keyed thereon, said shaft being retained in journal boxes 15, as in Fig. 2, which are supported upon a cross piece 16.

Adjacent to the sprocket wheel 12 is a 70 hopper 17 of any suitable construction, formed in said frame, which, at its lower contracted end, merges into an annular orifice 18 formed to slightly project within the rear head 10 of the revoluble mixer 75 body 20, said orifice permitting the material to be mixed to be passed from the hopper to the mixer body 20. The revoluble shaft 10, as indicated, is disposed lengthwise over and upon the supporting structure and has keyed 80 thereon, as shown in Figs. 1 and 2, outer and inner sprocket wheels 21 and 22, respectively, which in turn carry suitable actuating chains 23 passed over band sprockets 24 about the circumferential exterior of the 85 mixer body aforesaid. On the respective ends of this mixer body and adjacent the said band sprockets are formed trackways 25, which are adapted to contact with idlers 26 retained in brackets 27 secured to the sup- 90 porting structure, as in Figs. 3 and 4. This mode of construction enables the mixer body to be fixedly suspended.

As the material to be mixed enters the orifice 18 at the bottom of the hopper 17, it 95 engages a number of baffle or mixing plates 28, which extend lengthwise of the mixer body and are arranged at the proper spiral slope to insure a positive forward feed. This manner of positioning the baffle or 100 mixing plates provides adequate means for insuring a proper and constant forward feed of the material as it is revolved in the mixing chamber. These baffle or mixing plates have outwardly extending ledges 29, formed 105 at their forward ends, as in Fig. 2, for catching the mixed material preparatory to discharging the same. The front head 30 of the revoluble mixer drum has a central discharge opening 31 and is recessed on its 110 inner side, as at 32, which, in connection with the ledges 29, forms, in effect, a pocket.

The telescopic discharge chute is positioned just in front of the central discharge opening 31 of the front head, and comprises an outer curved fixed member 33 attached to 5 supporting brackets 34. An inner scoop-shaped movable section 35, of the same general formation as the outer fixed member 33, is capable of having its inner end 36 projected within the discharge opening, as indicated in dotted lines, and withdrawn, as 10 shown in Fig. 2. A cross bar 37 is secured over the inner movable section 35 and has a turn cap 38 thereon, through which is inserted an actuating lever 39, the outer end 15 of which is adapted to be held by the operator, and the inner end passes through a lever regulator 40, which limits the thrust of the lever in both directions, said lever being pivotally mounted on a bracket 41. In case 20 it is not desirable to employ sprocket chains and sprocket bands, as aforesaid, pulleys 42 may be keyed upon the revoluble shaft 10, and pulley grooves 43 about the periphery 25 of the movable mixer drum, as in Fig. 4, may be utilized in connection with a continuous rope or cable 44.

From the foregoing description it will be apparent that the device is especially adapted to be used for the purpose of properly mixing building materials; that the various parts and features used in the construction thereof are designed especially for durability; and that the means suspending the revoluble mixer drum add increased 35 efficiency to the mixer.

What I claim as new and desire to secure by Letters Patent is:

1. A rotary drum mixer having on its interior a plurality of continuous spiral baffle plates, each plate extending from front to rear of the drum and each plate at the discharge end of the drum having its inner corner projecting towards the center of the drum, forming at the forward end of each 40 plate a ledge, a head for the discharge end of the drum, the inner face of the head and the ledges of the plates forming a series of pockets, and means for revolving the drum, substantially as described.
2. A rotary drum having on its interior a plurality of continuous spiral baffle plates, each plate extending from front to rear of the drum and each plate at the discharge end of the drum having its inner corner projecting toward the center of the drum, forming at the forward end of each plate a ledge, a head for the discharge end of the drum and having a convex inner face, the inner 45 concave face of the head and the ledges of the plates forming a series of pockets, and means for revolving the drum, substantially as described.
3. A rotary drum mixer having on its interior a plurality of continuous spiral

baffle plates, each plate extending from front 65 to rear of the drum and each plate at the discharge end of the drum having its inner corner projecting towards the center of the drum, forming at the forward end of each plate a ledge, a head for the discharge end 70 of the drum the inner face of the head and the ledges of the plates forming a series of pockets, means for revolving the drum, and means for regulating the discharge of the mixed material dropped from the pockets, 75 substantially as described.

4. In a mixer, a mixing chamber having its head at the discharge end thereof recessed on its inner side, means for suspending the mixing chamber, angularly disposed 80 baffle plates within the mixing chamber for mixing and feeding forward the mixed material, said baffle plates having ledges formed thereon, means for revolving the mixing chamber, and means for regulating 85 the discharge of the mixed material, substantially as described.

5. In a mixer, a mixing chamber, angularly disposed baffle plates secured to the interior of the mixing chamber for mixing 90 and feeding forward the mixed material, said baffle plates having ledges formed thereon, the forward head of the mixing chamber being recessed on its inner side to form a pocket for the mixed material, means 95 for suspending the mixing chamber, a revoluble shaft, sprocket wheels keyed to the revoluble shaft, band sprockets about the mixing chamber, chains engaging the sprocket wheels and the band sprockets, and 100 means for actuating the revoluble shaft, substantially as described.

6. The combination in a rotary mixer, of a supporting frame, a revoluble mixing drum, a plurality of baffle plates on the interior of the drum, each baffle plate angularly disposed and extending from end to end of the drum, each baffle plate at its discharge end having its inner corner projecting toward the center of the drum, forming 105 at the forward end of each plate a ledge for mixing and feeding forward the material and catching and dropping the mixed material, and means for revolving the drum, substantially as described.

7. The combination in a rotary mixer, of a drum, a mixing drum inclosing a mixing chamber, a head for the discharge end of the drum, said head having a recessed face on its inner side, means for suspending the 120 drum, a plurality of baffle plates on the interior of the drum, each baffle plate angularly disposed and extending from end to end of the drum, and each baffle plate at its discharge end having its inner corner projected towards the center of the drum, forming at the forward end of each plate a ledge, for mixing and feeding forward the ma- 125

terial and catching and dropping the mixed material, and means for revolving the drum, substantially as described.

8. The combination in a rotary mixer, of a frame, a mixing drum inclosing a mixing chamber, a head for the discharge end of the drum, said head having a recessed face on its inner side, means for suspending the drum, a plurality of baffle plates on the interior of the drum, each baffle plate angularly disposed and extending from end to end of the drum, and each baffle plate at its discharge end having its inner corner projected to-

wards the center of the drum, forming at the forward end of each plate a ledge, for 15 mixing and feeding forward the material and catching and dropping the mixed material, means for revolving the drum, and means for regulating the discharge of the mixed material dropped from the ledges, 20 substantially as described.
